ADDRESSING MACHINE

Harmon P. Elliott, Watertown, Mass.

Application February 11, 1935, Serial No. 5,944

38 Claims. (Cl. 101—48)

This invention relates to printing or addressing machines of the type wherein the printed data is carried by a series of data bearing devices, and particularly by stencils.

5 This invention relates particularly to an addressing machine adapted for printing tax lists for municipal and county purposes. For the printing of tax lists the name of the property owner and a description of the property owned by him is carried by the same stencil, the address being above the description of the property. In transferring the data of the stencils to ledger sheets or the like, however, the address and the property description are required to be printed 10 side by side in the same horizontal line. Hence an object of the present invention is an improved machine for this purpose.

The machine of the present invention is particularly adapted for printing the addresses and the property description side by side on ledger sheets. For this purpose the machine is provided with two printing heads which are successively operable on the same stencil, one head being arranged to print the address portion only 15 and the other head being arranged to print the property description portion only of the stencil, the sheet being advanced between successive printing operations on the same stencil so as to position the address and the property description 20 in the same horizontal line. In the printing of separate sheets as contrasted with printing the data on a sheet of indefinite length the printing operation has to be modified at the start of each sheet in order for the address and property description to be printed in proper order on the sheet. The same is true with respect to the 25 printing of the last data on the sheet. Hence it is a further object of the invention to provide means for manually disabling the printing operations of either one, and both, of the two printing 30 heads at will.

Also for the same purpose it is desirable to interrupt or disable the sheet feeding mechanism and the provision of improved means for this 35 purpose is another object of the invention.

A yet further object of the invention resides in the construction of the machine whereby it can also be adapted to the printing of duplicate tax bills from the same stencils used in printing 40 the tax lists.

Tax lists have been printed heretofore by the use of two or more stencils for each owner of taxable property, one stencil bearing the address and the other, or others, the property descriptions. 45 The property description stencil did not contain

the owner's name and hence there was the liability of improper listing if the address and the corresponding property description stencils became separated in the stencil collection. Hence, for the present invention, a stencil is employed having a data bearing stencil sheet wide enough to bear both the address and the property description. 5

With such a stencil it becomes necessary to print only the address at one printing operation and only the property description at another printing operation. Such a stencil can not readily be used with, and such part printing accomplished by, the cylindrical ink-bearing impression roll heretofore employed, it not being 10 practical to compress the roll sufficiently to cover the required width of the data-bearing portion of the stencil and to use a mask or the like to shield the unwanted part of the stencil from the roll, due to the pressure on the mask, and for 15 other reasons. 20

Hence for the present invention, and as an object thereof, the impression device is a flat somewhat resilient ink-bearing pad supported and arranged in such a way as to function in an entirely satisfactory manner. A flat pad has been employed heretofore, but was so arranged that its flat impression surface moved always parallel with the face of the stencil. This arrangement I have found not to be satisfactory for uniform printing as air bubbles are entrapped between the contacting faces of the pad and the stencil that prevent the ink from covering the stencil uniformly. This action is particularly troublesome with broad contacting faces. 25 30

In accordance with my invention the flat pad, instead of being mounted for movement in parallel lines toward and away from the stencil, is mounted to swing in an arc toward and away from the stencil and thus to engage the stencil 35 progressively from one end to the other, thereby to squeeze out any air bubble that may tend to form and to drive the air out in advance of the line of contact, the pad being made of sufficiently yielding material to permit this action while exerting a substantially uniform pressure on the stencil throughout the contacting area. 40 45

A further object is to mount the impression pad so that the relation between its flat-ink-bearing surface and the stencil can be adjusted, or the pad levelled, to secure uniform printing of the data carried by that part of the stencil with which it is brought into pressure contact. 50

A further object is generally to improve the 55

construction and operation of an addressing machine.

Fig. 1 is a front elevation of a machine embodying the present invention.

5 Fig. 2 is a sectional detail taken along line 2-2 of Fig. 1.

Fig. 3 is a sectional detail of the operating mechanism of Fig. 2 taken along line 2-2 of Fig. 1 but showing the operating mechanism in more 10 complete form and also showing the selector mechanism.

Fig. 4 is a sectional detail taken along line 4-4 of Fig. 2 and illustrating especially the manually operable clutch connections between the printing 15 platens and the operating shaft.

Fig. 5 is a perspective view of a platen operating cam and its associated clutch mechanism.

Fig. 6 is a perspective detail of the sheet feed.

Fig. 7 is a plan detail of the pusher disabling 20 mechanism.

Fig. 8 is a sectional detail of the printing head.

Fig. 9 is a perspective view of a printing head plate.

Fig. 10 is a perspective view of a stencil used in 25 connection with the present invention.

Fig. 11 is a diagrammatic view of the relative positions of a tax list sheet and the printing heads and stencils.

Fig. 12 is a perspective detail, partly diagrammatic, of the printing heads and platens.

The machine embodying the present invention includes a horizontal table 16 having a pair of parallel rails 18 constituting a stencil track extended from one end to the other in spaced relation thereabove. A stencil holder 20 for a pile of superimposed stencils is disposed above the track at one end of the table and a pusher 22 is arranged to move the successive lowermost stencils of the pile out of the holder and along the 40 track into and out of a printing position and thence into a stencil receiver 24 that is located mainly below the track at the other end of the machine.

The machine is provided with two printing heads A and B, see especially Figs. 1, 2 and 12, 45 which heads are located side by side above the stencil track and are adapted to act successively on the same stencil in its successive positions in the track. Said heads are carried by forwardly 50 extended arms 26 of a reciprocable loop frame 28 pivoted at 30 to a bracket 32 disposed mainly beneath and secured to the table 16, the pivotal connection between the bracket and the loop frame being about at or somewhat above the top 55 line of the stencil track so that firm and uniform engagement between the entire printing face of the head and the stencil may be obtained. As the loop is under considerable strain when applying the printing pressure and thus is liable to bend at the ends, the bending is prevented by 60 thrust rollers 28a, supported by the frame of the machine and bearing on arcuate pads 28b of the loop at the ends thereof.

The heads are or can be identical in construction and but one will be described. Each printing head includes a pair of generally horizontal supporting arms 34, see especially Figs. 2 and 8, carried at their rear ends by a pair of superposed rigid parallel rods 36 and 38 that are extended 65 between and are carried by the arms 26 of the operating frame 28. The engagement of the supporting arms with both of said rods serves to hold the arms rigid with the arms 26 without relative pivotal movement therebetween. An 70 impression plate holder 40 is disposed close under 75

the arms 34 and has upwardly extended bosses 41 through which the lowermost rod 36 passes. Said plate holder is secured to said arms by leveling screws 42 and 44. The screws 42 pass loosely through said arms 34 and are screw-threaded 5 into the plate holder 40. The screws 44 are screw-threaded in said arms and bear against the top of the impression plate holder 40. By the provision of the aforesaid screws 42 and 44 the impression plate holder can be levelled as by 10 slackening off on a screw 42 and screwing down a screw 44 so that the impression plate can make uniform contact over its entire extent with the stencil.

The impression plate holder is provided at its 15 sides with a pair of cam plates 45 which are so arranged as to provide between them and under the lower face of the plate holder a dove-tailed slot 46 in which an impression plate 48 is retained 20 removably. The impression plate, see Figs. 8 and 9, comprises a flat metal plate 50, having inclined end faces that fit removably within the dove-tailed groove 46 of the impression plate holder and engage the cam plates 45. The upper 25 face of the plate 50 is provided with a recess 52 adapted removably to receive a locking pin 54 that is vertically movable in the impression plate holder 40 under urge of a plate spring 56. The impression plate is provided with a handle 58 which is adapted to be grasped in inserting and 30 removing the impression plate into and out of its holder; and the spring 56 is disposed in such position that it can be readily engaged and raised by a finger to free the holding pin 54 so that it will be raised upon the withdrawing movement of 35 the impression plate, thereby to permit the removal of said plate. The impression plate is provided with a sufficiently resilient, as a rubber or equivalent, plate or pad 60 that has an ink-bearing raised portion 62 having a flat stencil 40 engaging face that is as long as the data bearing portion of the stencil and as wide as a selected part of the data space of the stencil.

The stencil, see especially Fig. 10, consists of a 45 frame 64 carrying a stencil sheet 66 which is provided with an address-bearing zone 68 and a zone 70 occupied by a description of the taxed property, the two zones 68 and 70 being located one above the other.

The flat raised portion 62 of the impression 50 plate of the printing head B is located near the forward edge of the plate and is arranged to print the tax description 70 only. Figs. 8 and 9 are illustrative of this impression plate. The printing head A has raised and depressed portions, corresponding to the raised and depressed portions 60 and 62, respectively, of Fig. 9, arranged in reverse order as is illustrated by the dotted lines in Fig. 11, so as to print the address data 68 only of the stencil. Thus as the stencils 55 are moved in successive order along the stencil track the printing head B will print the tax descriptions 70 of the stencils and the printing head A will print the address data 68 of the stencils. 60

The impression faces of the impression plates are inked by a pair of rolls 72, one for each plate, journaled on a shaft 74, see especially Fig. 2, disposed below the printing heads and extended 65 between and secured to arms 76 pivoted at 78 to 70 downwardly extended swinging arms 80. Said arms 80 at their upper ends are pivoted on stud screws 82 secured to the forwardly extended ends of bracket arms 84 carried by and located above the table and head operating frame 28. A tensile 75

spring 86 is connected with the arms 80 and biases them for movement in a clockwise direction to carry the inking rolls 72 forwardly across the printing faces. This movement, however, is under control of a pair of links 88, the lower ends of which are pivoted by screws 90 each to a separate printing head A, B. Said links extend upwardly in overlying relation with the arms 80 and are provided with elongated slots 92 therein in which are disposed slide blocks 94 pivoted on pins 96 fixed to said arms 80. Adjusting screws 98 are screw-threaded in said arms and are adapted at times to bear against the lower faces of said blocks 94. The vertical movements of the printing heads move the links 88 and the screws 98 downwardly and upwardly and thus control the swinging movements of the arms 80. As a matter of fact, however, the screws 98 are relied upon principally to determine the limits to the swinging movements of said arms 80 and thereby the stroke of the inking rolls 72. The main swinging movement of the arms 80 is obtained by cam rollers 100 carried by said links 88, which rollers bear upon cam faces 102 on the lower or inner faces of the arms 80 and thereby effect the swinging movements of said arms.

Ink is supplied to the inking roll 72 by a cylindrical and rotatable ink reservoir 104 carried by pivoted arms 106 and bearing upon the periphery of an axially reciprocable continuously-rotated spreading roll 107 which is in driving engagement with the surface of a cylindrical transfer drum 108, each printing head having a separate ink supply spreading roll and a transfer drum. Ink from the surface of each transfer drum is conveyed to the inking rolls 72 by a series of conveyor rolls 110, 112, 114, journaled on rods 116 extended between and carried by depending arms 118 pivoted to the bracket arms 84 by the aforesaid screws 82. Each transfer drum has associated with it a set of the aforesaid conveyor rolls. The supporting rods for the rolls 110, 112, are loosely mounted in the arms 118 so that rolling contact between the conveyor rolls is assured. The uppermost set of conveyor rolls 110 engages the transfer drum in such a location that the series of conveyor rolls are maintained in a position illustrated in Fig. 2 in front of the printing heads. On each swinging movement of the inking roll 72 they are brought momentarily in rotating contact with the lowermost conveyor rolls 114, which rolls supply ink to the inking rolls. The construction of the inking mechanism herein described is described in greater detail and is claimed in my copending application Serial No. 5,945 filed February 11, 1935.

The arrangement of the printing head is so arranged that, as it swings downwardly above the pivot 30 toward the stencil, the heel of the resilient impression pad or plate 60, or that part nearer the pivot 30, first makes engagement with the stencil and yields to permit the line of contact to advance in a progressive manner to the toe of the pad. This manner of contact sweeps out air that otherwise might be entrapped between the contacting surfaces and hence permits uniform printing to be obtained. The angle that the ink-bearing face of the pad makes with the stencil at the initial contact with the stencil need be but slight, so that the pressure between the pad and the stencil, when in full contact, can be substantially uniform throughout. The proper setting of the pad is obtained by proper adjustment of the leveling screws 42, 44.

75 A printing head as thus described is disclosed

but not claimed in my copending application Serial No. 697,407, filed November 10, 1933.

The operating mechanism for the printing elements includes an operating shaft 120, see especially Figs. 1, 2, 3, and 4, journaled in downwardly extended arms 122, see especially Figs. 2 and 4, of the aforesaid bracket 32 beneath the table 16. Said shaft is reciprocated by means including a sector 124 which is fixed to said shaft and is pivotally connected to the upper end of a connecting rod 126, see Figs. 1 and 3, which connecting rod is reciprocated by a power plant 128 of common construction unnecessary to describe in greater detail here except to state that the reciprocation of the connecting rod is controlled by a foot pedal 130, the depression and immediate release of said pedal effecting a complete outward and return stroke of said connecting rod. The sector 124 is connected through a latch 125 with an operating arm 127 that is fixed to the shaft 120 so that reciprocation of said sector when latched to said arm also effects the conjoint reciprocation of said arm. The engagement of the latch is controlled by selector controlled mechanism illustrated in Fig. 3 of a well known construction not necessary to explain in detail. The arm 127 is connected through a toggle linkage 129 to the depending arm 29 of the printing head frame 28 and straightens to exert a strong printing pressure on the engaged stencil and work sheet.

The printing mechanism includes a pair of platens 132, each platen cooperating with a separate head A and B, and having a flat upper face that is about coextensive with the area of the stencil sheet of the stencil. Said platens are carried by the forward ends of arms 134 pivoted to the frame of the machine. The platens are reciprocable in a vertical direction through openings in the table 16 into a position to hold a work sheet close under the stencil sheet of a stencil, thereby to support it against the printing pressure of a printing head during the printing operation.

The reciprocatory movements of the two heads are controlled by cams 136, 138, see especially Fig. 4, disposed upon and reciprocated by the shaft 120. Each cam is provided with a forwardly extended portion 140 which is free to ride under a cam roller 142, see especially Fig. 3, of the platen without reciprocating the platen. The cam is also provided with an operating portion 144 that serves to raise the platen into its elevated working position. The cam is further provided with an elevated dwell portion 146 that permits further movement of the cam member while maintaining the platen in elevated position.

The cams 136 and 138 are loose upon the shaft 120 and are clutched thereto by manually operable clutch mechanism which is the same in construction for each cam member. With respect to the cam member 136 the clutch mechanism, see especially Figs. 4 and 5, includes a narrow plate 148 which is secured to the hub of the cam member and is extended parallel with the shaft 120 and has a forwardly extended handle 150 disposed in position conveniently to be grasped by an operative standing at the front of the machine. A latch member 152 is pivotally connected at 154 with the handle member and has the part 156 that is parallel with the plate 148 and carries a clutch pin 158. Said pin is extended loosely through a hole in the plate 148 and is adapted to enter an axial slot 160 in a collar 162 fixed to the operating shaft 120 adja-

cent the cam member. Thus when the clutch pin 158 is located in the slot of the collar the cam member and the shaft are restrained for conjoint reciprocatory movement. When, however, the clutch pin is withdrawn from the notch of the collar the cam member is operatively disconnected from the operating shaft so that said shaft can oscillate with the corresponding movement of the cam member. The arrangement is such that when the cam member is to be disconnected from the operating shaft the clutch handle is grasped and the latch 152 depressed against the action of the spring 164 to pull the clutch pin out of the notch of the collar. The handle is then raised upwardly to swing the cam member 136 in a clockwise direction until the clutch pin engages a stop 166 of the collar or until the cam member has been moved into the dotted line position, as shown in Fig. 2. The tail 140 of the cam member is sufficiently long to permit this displaced position of the cam member without moving it out from under its co-operating platen. In this displaced position of the cam member the reciprocation of the operating shaft can take place without moving the cam in a counterclockwise direction, as viewed in Figs. 2 and 3, sufficiently far to effect the raising of the platen into printing position. Thus the printing head can descend upon a stencil without effecting the printing thereof. The cam 138 is similarly provided with a handle 168 and similar clutch mechanism for controlling the connection of the cam member with the operating shaft. The reasons for the clutch connection between the operating shaft and the cam members will be explained hereinafter.

The reciprocatory movement of the stencil pusher 22 is effected by the reciprocatory movement of the sector arm 124. A vertically pivoted hub 170, see Figs. 1 and 7, has a horizontally extended arm which is terminated in the cam slot 172 of the sector 124 and the arrangement is such that the reciprocatory movement of the sector causes a corresponding reciprocatory movement of said hub 170. Said hub is provided with a horizontal and forwardly extended arm 174 that is pivoted at its forward end of a link 176 that at its other end has a longitudinally disposed slot 178 therein, which slot at its extreme end is provided with a lateral extension 180. A pin 182 of said pusher is disposed in said slot 178 and in the normal operation of the machine is disposed in the lateral extension 180 thereof so that the reciprocatory movements of the links 176 effect the corresponding movements of the pusher. The link and pin are normally held in such relation by a pivoted arm 184 carrying rolls 186 and 188. The roll 186 engages the slotted end of the link 176 and the other roll engages a multi-lobed cam 190. When the roller 188 is located in a depression between the lobes of said cam the link 176 is held in operative engagement with the pusher. When, however, said cam is rotated to move one of said lobes against said roll 188 such movement causes the slot 178 of the link 176 to be aligned with the pin 182 and thereby to effect the disengagement of said link and pusher. Thus a printing operation can be effected without a stencil advancing operation. The rotation of the lobed cam 190 is under control of a link 192 reciprocated by the arm 174. The mechanism is not necessary to describe except to state that it is used when the machine is arranged to print duplicate or triplicate tax bills in which event the cam 190 will be rotated

by one-half the distance between two consecutive lobes for each two or three printing operations depending upon whether duplicate or triplicate bills are made.

In connection with the clutch mechanism for controlling the printing operation of the two printing heads it is also desirable to control the stencil feeding operation and at times to prevent the feeding of a stencil. This control is manually effected by the operator of the machine. For this purpose the machine is provided with a foot pedal 194, see especially Fig. 1, pivoted to the frame of the machine intermediate its ends and connected at the other side of its pivotal support with an upwardly extended link 196, which link at its upper end is pivotally connected to a forwardly extended arm 198 of a shaft 200 journaled in a bracket 202, depending from the lower face of the table 12 in front of the operating link 176 for the pusher. Said shaft 200 has an upwardly extended arm 204 fixed thereto. Said arm at its upper end carries a roller 206 that is disposed in front of and is adapted to cooperate with an extension 208 of the arm 184. The arrangement is such that when the pedal member 194 is depressed said roller 206 is moved into engagement with the extension 208 to cause said arm 184 to swing outwardly about its pivot and displace the pusher operating link 176 sufficiently to bring the slot 178 thereof into line with the pin 182 of the pusher, thereby to disconnect said link and pusher so that a printing operation can be effected without a corresponding stencil advancing operation.

A work sheet 210 is adapted to be disposed upon the table 16, see especially Fig. 2, under the stencil track and above the platen and to be advanced toward the rear of the machine by a distance corresponding at least to the width of one of the data bearing portions of the stencil at each printing operation. The sheet advancing means comprises a shaft 212, see especially Figs. 1, 2 and 6, rotatably supported above the table in the rear of the stencil track. Said shaft has feed rolls 214 fixed thereto. Idler rolls 216 cooperate with said feed rolls in pressing the sheet against the feed rolls. Said idler rolls are disposed below the feed rolls and are journaled on said arms 218 of a lever that is pivoted intermediate its ends on a shaft 220 carried by a bracket 222 fixed to the under side of the table. Said lever has a forwardly extended end 224 which is pressed downwardly by a helical spring 226 to hold the idler rolls 216 normally against the sheet in engagement with the feed rolls 214. It is at times desirable to disable the sheet feed under control of the operative. To this end a foot pedal 228, see Fig. 1, is provided, the pedal being connected by a link 230 to an arm 232 fixed to a shaft 234 journaled in a bracket 236 secured to the under side of the table. The shaft 234 has an arm 238 fixed thereto that terminates in a roller 240 disposed under the forwardly extended end of the idler roll supporting lever 219. Thus when the pedal 228 is depressed the rod 230 is raised, causing the roll 240 to bear against the under side of the lever and rotate it in a clockwise direction, thereby moving the idler rolls away from cooperative relation with the feed rolls and stopping the advance of the sheet.

The feed rolls 214 are advanced in an intermittent or step by step manner by mechanism now old in the art. The feed roll shaft 212 is connected by gearing 242 to a shaft 244 having a one-way clutch or rotation mechanism 246 of

which one element is secured to the shaft 244 and the other element is secured to the crank 248. The crank is pivotally connected to a link 250 having a pivotal connection with an arm 252 of the reciprocating operating frame 28 for the printing heads. The arrangement is such that the movement of said frame in one direction effects the rotation of the feed rolls in one direction while the movement of the frame in the opposite direction takes place, by reason of the one-way clutch mechanism 146, without a corresponding movement of said rolls.

Fig. 11 illustrates a tax list sheet adapted to be printed by the machine as above described. Said sheet 210 is provided with two vertical columns 254 and 256, each column having a series of vertically arranged print receiving sections 258 that are arranged in horizontal line. The spacing of the columns is such that they can be positioned beneath the two printing heads A and B to receive the data of said heads. The left hand column 254 is adapted to receive the addresses from the address zone 68 of the stencil and the right hand column 256 is adapted to receive the property description from the zone 70 of the stencil. The address of any one stencil is adapted to be printed in the left hand column and the property description of the same stencil in the right hand column, the address and the property description being disposed in the same horizontal line, although in the stencil the address and the description are in vertical line. For this purpose the tax description is printed in the right hand column by the printing head B. The stencil is then moved into position under the printing head A and the work sheet 210 is advanced by the width of one column, thereby positioning the address data of the stencil under the stencil printing head over the left hand column to apply the address data in the same horizontal line with the tax description.

The clutch mechanisms that control the effective operation of the printing platens 132 are desirable at the beginning of printing a new sheet and at the end of the printing of a sheet when the last line of a sheet is being printed. A stencil entering the first printing position under the printing head B has its tax description data recorded in the right hand column. The stencil is then advanced to the printing head A and the sheet is advanced one line. At the next printing operation the address corresponding to the previously printed tax description data is applied by that stencil in the left hand column. The movement of the stencil from the head B to the head A is, however, accomplished by moving another stencil under the printing head B and if a printing operation were effected upon this second stencil, the property description data of that stencil would be printed on the sheet below the column or the sheet would be smudged. Hence the printing mechanism associated with the head B is disabled at the time of printing the last line of the left hand column. This is effected by manipulating the clutch handle 168 to disengage the platen operating cam 138 from the operating shaft 120, and raising the handle to rotate the cam out of operative relation with the platen. Thus while both printing heads may descend during the printing operation printing will be effected only from the left hand stencil.

The position of the stop pin 166 associated with the clutch handle 168 is such that the shaft 120 at the end of its stroke positions the notch in 75 the clutch collar 162 in line with the clutch pin

158 so that the clutch after having been manually disconnected is automatically re-engaged. At the same time that the clutch mechanism is disengaged the stencil advancing mechanism is also disabled, so that the printing operation can be effected without an associated stencil advancing mechanism, it being necessary that the second stencil be retained under the printing head B to print on the top line of the next sheet to be inserted. The disabling of the printing mechanism is accomplished by depressing the lever 194 in the manner hereinbefore described. Thus when the address in the last line of the left hand column of the sheet is to be printed the platen of the right hand printing head B is disabled and the stencil advancing mechanism is also disabled. When a new sheet is inserted in place of the filled sheet the right hand clutch mechanism is restored to its normal driving engagement and the stencil advancing mechanism is also restored to its normal operative condition so that the second stencil can print its tax data in the top line of the right hand column of the new sheet. If, however, a printing operation was performed on both the first and the second stencils, the first stencil having had its address applied to the bottom of the previous sheet, this same address would be applied to the new sheet above the first line and thus damage the sheet. Hence the left hand clutch mechanism is operated to prevent the operation of the printing platen associated with the left hand printing head A. Thus for beginning the printing of a new sheet the left hand clutch mechanism is thrown out for one printing operation and for terminating the printing of the sheet the right hand clutch mechanism is thrown out and the stencil advancing mechanism is disabled for one printing operation.

The machine is also designed to function in more or less the usual manner as an addressing machine, particularly for sending out tax bills in duplicate or triplicate, as may be desired, from the same collection of stencils employed and printing the tax list sheets. To this end one of the printing heads, preferably the printing head B, has its impression plate 48 replaced by one, not necessary to illustrate, that bears upon the stencil over its full active face so that both the address and the property list are printed at the same operation. The other printing head is permanently disabled by maintaining its clutch in disengaged position. The machine is provided with selector mechanism 260, see Fig. 1, now more or less common in the art, which, under the control of the stencils, controls the energization of an electromagnet 262 that actuates mechanism 264, see Fig. 3, that in turn controls the engagement and disengagement of the latch 125 which connects the operating sector 60 124 with the operating arm 127 for the shaft 120. Each stencil may have a selector perforation 266, see Fig. 10, and the selector mechanism may have one selector pin 268, which registers with the perforations so as to effect a printing operation when the pin can pass into a perforation. By inverting the stencils of the collection as the tax bills are paid, the machine will operate to print tax bills only for those addresses that have not been inverted.

I claim:

1. In an addressing machine of the type operable upon a succession of printing devices and having means to support the successive devices in printing position, the combination therewith

of a printing head comprising a swinging frame having an arm movable toward and away from said supporting means, an impression plate holder carried by said arm, and an impression plate 5 carried removably by said holder, said impression plate holder and said impression plate having an interfitting tongue and groove connection, said holder having manually releasable means locking said plate removably to said holder, an 10 ink roll adapted to travel forwardly and rearwardly over the face of said impression plate, and inking means for said ink roll comprising a pivoted conveyor frame hanging in front of said impression plate and having ink conveyor 15 rolls the lowermost one of which is adapted to be engaged by said ink roll in the forward part of its movement, said frame being capable of swinging upwardly away from position in front of said impression plate to permit engagement 20 and withdrawal thereof from said holder.

2. In an addressing machine of the type operable upon a succession of printing devices and having means to support the successive devices in printing position, the combination therewith 25 of a printing head comprising a swinging frame having an arm movable toward and away from said supporting means, an impression plate holder carried by said arm, and an impression plate carried removably by said holder, said impression 30 plate having a handle which upstands in front of said plate holder and said plate holder having means operative to lock said plate releasably to said holder, manually operative means disposed adjacent said handle for releasing the lock on said plate, an ink roll adapted 35 to travel forwardly and rearwardly over the face of said impression plate, and inking means for said ink roll comprising a pivoted conveyor frame hanging in front of said impression plate 40 and having ink conveyor rolls the lowermost one of which is adapted to be engaged by said ink roll in the forward part of its movement, said frame being capable of swinging upwardly away from position in front of said impression plate 45 to permit engagement and withdrawal thereof from said holder.

3. An addressing machine of the type operable upon a collection of printing devices and having means to support the successive devices in printing 50 position, the combination therewith of a printing head comprising a swinging frame having a pair of forwardly extended arms movable toward and away from said supporting means, a pair of spaced rods extended between and carried by said arms, and impression plate supporting means carried by said rods.

4. An addressing machine of the type operable upon a collection of printing devices and having supporting means for the successive devices in 60 printing position, the combination therewith of a swinging printing frame having a plurality of spaced forwardly extended arms movable toward and away from said supporting means, a pair of rods extended between and carried by all of 65 said arms, and an impression plate supporting means carried by said rods between each pair of arms.

5. In a stencil printing machine, the combination of a resilient ink-bearing impression pad 70 and a platen disposed on opposite sides of the stencil, an angularly swinging arm movable toward and away from the stencil and carrying said pad, the pad moving angularly of the stencil with said arm, said pad having a resilient flat ink-bearing and stencil-engaging face and being

so mounted that it initially angularly engages the stencil and upon continued movement toward the stencil engages the stencil in a progressive pressure applying manner and yields in engagement therewith and finally engages the stencil 5 over the full area of the pad with substantially uniform pressure throughout.

6. In an addressing machine of the type operable on a stencil, the combination of a resilient impression pad having a flat ink-bearing stencil-engaging face, and an angularly swinging arm carrying said pad rigid therewith and operative to effect the initial angular engagement between said pad and stencil at one edge of said flat face and thereupon to compress said pad and to progressively advance the area of engagement between said face and stencil until the pad engages throughout its effective area with the stencil and exerts pressure uniformly thereover. 10 15

7. An addressing machine of the type adapted 20 to print addresses contained in a collection of stencils or similar printing devices on long sheets, including a printing frame in the form of a horizontal loop through which the sheet is adapted to pass, pivotal supporting means for the loop 25 engaged with the middle portion of the bottom part thereof, printing means carried by the middle portion of the upper part of the loop, toggle means for reciprocating the loop, and means bearing against the ends of the loop in a direction to resist deflection thereof under the action of said toggle means. 30

8. A stencil addressing machine including a work supporting anvil on one side of the stencil normally movable into and out of work supporting position, a printing head on the other side of the stencil having a flat face movable into and out of engagement with the stencil, means for normally reciprocating said printing head and anvil, and means for disabling the operation of 40 said anvil while permitting reciprocation of said printing head. 45

9. An addressing machine as in claim 8, said anvil disabling means being controllable at the will of the operative. 50

10. An addressing machine operative upon stencils comprising an anvil disposed on one side of the stencil normally reciprocable into and out of a work supporting position, a printing head on the other side of the stencil having a flat face 55 reciprocable into and out of engagement with the stencil, means normally operative to reciprocate said printing head and anvil conjointly, and means operative to arrest the reciprocatory movement of said anvil alone. 55

11. An addressing machine operative upon stencils comprising an anvil disposed on one side of the stencil normally reciprocable into and out of a work supporting position, a printing head on the other side of the stencil having a flat face 60 reciprocable into and out of engagement with the stencil, means normally operative to reciprocate said printing head and anvil conjointly, and means operative to arrest the reciprocatory movement of said anvil alone with said anvil 65 positioned away from its work supporting position.

12. An addressing machine operative upon stencils comprising a work supporting anvil disposed on one side of the stencil and reciprocable 70 into and out of work supporting position, a printing head on the other side of the stencil having a flat face reciprocable into and out of engagement with the stencil, mechanism for reciprocating said anvil and printing head normally con- 75

- jointly, including means for reciprocating said anvil, and means for disabling said anvil reciprocating means whereby to hold said anvil alone out of its work supporting position during the 5 reciprocatory movement of said printing head.
13. An addressing machine operative upon stencils comprising an anvil disposed on one side of the stencil and reciprocable into and out of a work supporting position, a printing head on the 10 other side of the stencil having a flat face reciprocable into and out of engagement with the stencil, mechanism for reciprocating said head and anvil including an oscillating cam for reciprocating said anvil, and means for preventing the reciprocation of said anvil including means for operatively disconnecting said cam from said reciprocating mechanism, said mechanism being operative to reciprocate said printing head when said cam is disconnected.
- 20 14. An addressing machine operative upon stencils comprising an anvil disposed on one side of the stencil and reciprocable into and out of a work supporting position, a printing head on the other side of the stencil having a flat face reciprocable into and out of engagement with the stencil, mechanism for reciprocating said head and anvil normally conjointly, and means for preventing the reciprocation of said anvil independently of said printing head, including 25 an oscillatory shaft, an oscillatory cam oscillated by said shaft, and means for disabling the operative connection between said cam and shaft.
15. An addressing machine comprising an anvil reciprocable into and out of work supporting 30 position, a printing head reciprocable into and out of work engaging position, mechanism operative to reciprocate said platen and printing head normally conjointly including an oscillating cam for reciprocating said printing head, an oscillating shaft for reciprocating said cam, and a disconnectible clutch connection between said cam and shaft.
16. An addressing machine comprising an anvil reciprocable into and out of work supporting 35 position, a printing head reciprocable into and out of work engaging position, mechanism operative to reciprocate said platen and printing head normally conjointly including an oscillating cam for reciprocating said printing head, an oscillating shaft for reciprocating said cam, and a disconnectible clutch connection between said cam and shaft, said clutch connection being normally set to effect a driving engagement between said cam and shaft, said mechanism having 40 an operative connection with said printing head to reciprocate it when said clutch connection is disconnected.
17. An addressing machine adapted for operation upon a collection of printing devices comprising a guideway along which a succession of printing devices are moved in endwise contact through printing positions, a holder for a stack of printing devices, means for delivering successive devices from said holder into said guideway and for applying pressure endwise of the line of devices in said guideway for advancing them therealong, two printing mechanisms operable on the successive printing devices, said delivering and advancing means being operable to advance the printing devices successively from one to the other of said printing mechanisms, means for effecting the conjoint printing operation of both mechanisms upon successive printing devices, and means for preventing the printing operation 45 of one of said printing mechanisms while permitting the printing operation of the other printing mechanism and the operation of said delivering and advancing means.
18. An addressing machine adapted for operation upon a collection of printing devices comprising a guideway along which a succession of printing devices are moved in endwise contact through printing positions, a holder for a stack of printing devices, means for delivering successive devices from said holder into said guideway 50 and for applying pressure endwise of the line of devices in said guideway for advancing them therealong, two printing mechanisms operable on the successive printing devices, said delivering and advancing means being operable to advance the printing devices successively from one to the other of said printing mechanisms, means for effecting the conjoint printing operation of both mechanisms upon successive printing devices, and means for preventing the printing operation 55 of one of said printing mechanisms while permitting the printing operation of the other printing mechanism, said last named means being operative at the will of the machine operator and the operation of said delivering and advancing means.
19. An addressing machine as in claim 17, each printing mechanism having associated with it means for preventing the operation thereof.
20. An addressing machine as in claim 17, each 60 printing mechanism having associated with it means for preventing the operation thereof, both operation preventing means being operable each independently of the other.
21. An addressing machine for printing in a horizontal line data contained in a vertical column on a printing device comprising means to advance such devices in successive order intermittently through a printing position, two printing mechanisms conjointly operable on successive printing devices, one printing mechanism having means operative to print one portion only of the printing data on the printing device and the other printing mechanism having means operative to print another portion only of the printing data, means to advance a sheet through the printing position in a step by step manner so that the data printed by both mechanisms from the same printing device is in the same horizontal line on the sheet, and means to prevent the printing operation of one of said mechanisms during the printing operation of the other mechanism.
22. An addressing machine for printing in a horizontal line data contained in a vertical column on a printing device comprising means to advance such devices in successive order intermittently through a printing position, two printing mechanisms conjointly operable on successive printing devices, one printing mechanism having means operative to print one portion only 65 of the printing data on the printing device and the other printing mechanism having means operative to print another portion only of the printing data, means to advance a sheet through the printing position in a step by step manner so that the data printed by both mechanisms from the same printing device is in the same horizontal line on the sheet, and means operative to prevent the printing operation of any one of said printing mechanisms while permitting the printing operation of said other printing means.
23. An addressing machine for printing in a horizontal line data contained in a vertical column on a printing device comprising means to advance such devices in successive order inter- 70

- mittently through a printing position, two printing mechanisms conjointly operable on successive printing devices, one printing mechanism having means operative to print one portion only 5 of the printing data on the printing device and the other printing mechanism having means operative to print another portion only of the printing data, means to advance a sheet through the printing position in a step by step manner so that 10 the data printed by both mechanisms from the same printing device is in the same horizontal line on the sheet, and means operative to prevent the printing operation of any one of said printing mechanisms while permitting the printing 15 operation of said other printing means, said last named means being selectively operable at the will of an operative.
24. An addressing machine comprising a pair of printing mechanisms, means for advancing a 20 succession of printing devices to said mechanisms and successively from the action of one to the action of the other mechanism, means for normally operating said printing mechanisms conjointly upon successive printing devices, and 25 means for disabling the operation of one printing mechanism while permitting the operation of the other printing mechanism.
25. An addressing machine comprising a pair of printing mechanisms, means for advancing a 30 succession of printing devices to said mechanisms and successively from the action of one to the other of the other mechanisms, means for normally operating said printing mechanisms conjointly upon successive printing devices, and 35 means for disabling the operation of one printing mechanism while permitting the operation of the other printing mechanism and the operation of said advancing means.
26. An addressing machine comprising the 40 combination of two printing mechanisms, means for advancing a succession of stencils through the action of both mechanisms and successively from one mechanism to the other mechanism, said mechanisms each comprising a work supporting 45 anvil reciprocable into and out of a work supporting position, a printing head reciprocable into and out of work engaging position, means for selectively disabling the reciprocatory movements of said anvils, and means for reciprocating 50 said printing heads when said anvils are disabled.
27. An addressing machine comprising the 55 combination of a pair of printing mechanisms, means for advancing printing devices in successive order through said mechanisms and the printing devices in succession from one to the other mechanisms, each mechanism comprising a work supporting anvil reciprocable into and out of work supporting position, a printing head 60 reciprocable into and out of work engaging position, means for reciprocating said anvils normally conjointly comprising a reciprocable shaft, cams on said shaft engageable with said platens, and a clutch mechanism releasably connecting a 65 cam with said shaft, said clutch mechanisms being separately and independently operable, and means for reciprocating said printing heads conjointly when said cams are operatively disconnected from said shaft.
70. 28. An addressing machine comprising two printing mechanisms, means for advancing a succession of printing devices successively through said mechanisms and in succession from one to the other mechanism, means for operating 75 said printing mechanisms normally con-
- jointly, and means including a pair of manually operable control members for effecting the selective disabling of said printing mechanisms.
29. An addressing machine comprising two printing mechanisms, means for advancing a succession of printing devices successively through said mechanisms and in succession from one to the other mechanism, means for operating said printing mechanisms normally conjointly, and means including a pair of manually operable control members for effecting the selective disabling of said printing mechanisms independently of said device advancing means. 5
30. An addressing machine comprising the combination of a pair of printing mechanisms, 15 means for advancing a succession of printing devices through said mechanisms and in succession from one to the other mechanism, means for advancing a sheet common to both mechanisms through said mechanisms, means for normally 20 operating said printing mechanisms conjointly, and means including a control member for each printing mechanism for selectively disabling said printing mechanism. 10
31. An addressing machine including two 25 printing mechanisms, means to advance a succession of printing devices to the successive operation of said mechanisms, manually operative means to disable the operation of said printing mechanisms, selected at will, and other manually 30 operated means separately operable to disable the operation of said advancing means.
32. An addressing machine comprising the combination of a pair of printing mechanisms, 35 means to operate said printing mechanisms normally conjointly, means to advance a succession of printing devices through said printing mechanisms and in succession from one to the other mechanism, manually controlled means to disable the operation of a selected one of both of said 40 printing mechanisms while permitting the operation of the other mechanism, and other manually operable means separately operable to disable the operation of said device advancing means. 40
33. An addressing machine comprising the 45 combination of two printing mechanisms, means for advancing successive printing devices through said mechanisms and in succession from one to the other mechanism, each printing mechanism comprising an anvil reciprocable into and out of 50 work supporting position, a printing head reciprocable into and out of work engaging position, means for reciprocating both printing heads and anvils normally conjointly, manually operable means for disabling the operation of a selected 55 one of both anvils while permitting the operation of the other anvil and both printing heads, and manually operable means for disabling said advancing means while permitting the operation of said printing mechanisms. 60
34. An addressing machine of the type operable upon a collection of printing devices and having means to support the successive devices in printing position, the combination therewith of a printing head comprising a swinging frame 65 having a pair of forwardly extended arms movable toward and away from said supporting means, a rod extended between and carried by said arms, an impression plate carrier carried by said rod, and means engaged with said arms 70 and carrier for securing said carrier in set position on said rod. 70
35. A printing machine comprising two sets of pressure applying printing devices disposed on opposite sides of the stencil and operative to press 75

the stencil and work into engagement, means for advancing a succession of printing devices to the successive actions of said sets, means normally operative to effect conjoint operation of both 5 sets of devices, and means for preventing operation of one of said devices, whereby to prevent the printing operation of one of said sets of devices.

36. A printing machine comprising a pair of 10 printing heads, a common supporting structure for both heads, means for operating said structure to effect a printing operation of said heads, a pair of platens cooperating with said heads, means for normally operating said platens with 15 said heads, and means for preventing normal operation of one of said platens.

37. An addressing machine operating upon a succession of address bearing devices, said machine including a work supporting anvil disposed

on one side of an address bearing device and normally movable toward and away from cooperative printing relation therewith, a printing head on the other side of said address bearing device movable toward and away from cooperative printing relation with the device, means for normally reciprocating said printing head and anvil conjointly, and means for preventing the aforesaid movement of said anvil and for maintaining said anvil out of cooperative printing relation with a printing device while permitting the aforesaid movement of said printing head, whereby to prevent a printing operation on a selected printing device. 5 10

38. An addressing machine as in claim 37, the 15 means for preventing the movement of said anvil being controllable at the will of the operative.

HARMON P. ELLIOTT.
